ATTORNEY

UNITED STATES PATENT OFFICE

HENRY W. PARKER, OF TORONTO, ONTARIO, CANADA, ASSIGNOR TO ROGERS RADIO TUBES, LIMITED, OF TORONTO, CANADA, A CORPORATION OF ONTARIO

THERMIONIC TUBE

Application filed August 22, 1931. Serial No. 558,675.

My invention pertains to electron discharge devices of the type known as thermionic tubes and relates specifically to thermionic tubes employing the negative resistance or dynatron effect for their operation.

The dynatron or negative resistance effect in thermionic tubes is well known, but has hitherto not been of much commercial importance, owing to the fact that a dynatron-type of tube as heretofore constructed when used as an amplifier employed in more than one stage of amplification requires quite elaborate band pass filters to correct the tendency of very sharp side band cut-off which is inherent in such tubes and further, as it has hitherto been thought impossible to provide the necessary copious secondary emission of electrons which is essential to achieve a sufficiently steep characteristic of the anode current for satisfactory operation.

An object of my invention comprises providing a thermionic tube whereby the dynatron effect may be commercially utilized in radio frequency amplification.

25 A further object comprises providing a thermionic tube utilizing negative resistance phenomena and achieving high values of radio frequency amplification.

A still further object comprises providing 30 a thermionic tube having a high value source of secondary emission within the tube for achieving effectively the dynatron effect.

A still further object of my invention comprises providing a thermionic tube with an 35 electrode having a surface adapted to have a high secondary to primary electron emission ratio to provide a steep characteristic of the anode current.

I accomplish all of the above desirable features and eliminate the above mentioned undesirable features by providing a tube in which one of the electrodes, preferably a screening grid in close proximity with the anode, carries attached thereto small portions

45 of a metal of low atomic number and large atomic volume, and providing means attached to the screening electrode whereby during the course of manufacture of the tube the beads or portions of metal of low 50 atomic number may be vaporized from the

screening grid and distilled upon the anode to provide a mirror-like uncontaminated surface capable of high secondary electron emission for cooperation with two additional properly spaced and related screening electrodes. 55

My experiments with a tube so constructed have proven that a negative anode resistance may be obtained which is lower in value than has hitherto been deemed possible in such a 60 tube when used as a radio frequency amplifier.

I have obtained experimentally through the use of a tube constructed according to my invention stable radio frequency amplification per stage of an order higher than has hitherto been deemed possible by those familiar with the art. 65

In the drawing accompanying and forming a part of this specification and in which like reference numerals designate corresponding parts throughout:

Fig. 1 illustrates a broken plan view of the top of my improved tube.

Fig. 2 illustrates a partially sectioned view 75 of the assembly of the electrodes in the stem of my improved tube, with the enclosing envelope omitted for purposes of clarity.

Referring now particularly to the figures, my tube comprises the usual stem and press 80 1 supporting the anode 8 by means of the standards 13 and 17, one of which, 17, serves as a terminal therefor. The anode is preferably constructed of nickel or other metal having a relatively high melting point. 85

A screen electrode 10 is provided closely adjacent to the inner surface of the anode 8 and there is attached to the standards of this screen, in any suitable manner such as by spot welding, small portions 21, 22, 23 and 24 90 of a metal of low atomic number and large atomic volume, such as aluminum, boron, or beryllium, or an alloy of one or more of these metals.

A cathode 6, which is shown as of the indirect heated type but which may be obviously of the heated filament type either coated with electron emissive substances or not as desired, is centrally located with respect to the anode 95 8 and provided with terminals as shown. 100

Surrounding the cathode and in relatively close proximity thereto, there is provided the usual control grid 4 to which is attached the terminal 5. Between the control grid 4 and the inner anode screen 10, there is provided a further screen electrode 11. Surrounding the anode 8, on the outside thereof, there is provided an additional screen electrode 7. The screen 11 is connected to screen 10 by strap 25 and also connected to screen 7 by strap 9. The screens 7, 10 and 11 are supported in the press by the supports 12 and 18 respectively, one of which, 12, serves as a terminal therefor.

15 The cathode heater terminals are connected to supports 14 and 15 which also serve as terminals therefor, while a terminal 16 is provided for the active cathode element. All of the electrodes of the tube are maintained 20 in their relative positions by means of insulating disks 2 and 3 of refractory material.

Screen electrode 11 serves to provide an accelerating potential for the electrons emitted 25 from the cathode and which are controlled by the control grid 4. Screen electrode 10, which is preferably maintained in quite close proximity to the inner surface of the anode 8, serves a double purpose. It provides a positive potential gradient close to the inner surface of the anode 8 for the purpose of collecting slow moving electrons emitted from the anode by providing such a steep positive potential gradient that the negative potential 30 space charge caused by the slow moving secondary electrons does not function to prevent these slow moving electrons from moving in the direction of the potential applied by the screen. If this screen electrode 10 is removed to a considerable distance from the anode, a negative potential gradient would be produced at the immediate surface of the anode by the large number of slow moving secondary electrons emitted from the anode 45 by bombardment of the fast moving primary electrons arriving directly from the cathode through the mesh of the screen. This negative space charge of secondary electrons close to the anode I will refer to hereinafter as the secondary space charge, and the close proximity of screen electrode 10 to anode 8 is desirable to overcome this secondary space charge in order to obtain the maximum dynatron effect.

50 55 Further, screen electrode 10 serves to provide a high value of amplification constant for the tube as described in my co-pending application Ser. No. 505,045, filed December 27, 1930.

60 65 Screen electrode 7 serves to minimize the direct capacity between the anode and control grid 4 and such reduction of capacity is desirable when the tube is to function as a high gain voltage radio frequency amplifier.

65 Experimentally I have been able to, by

the use of a tube constructed in accordance with the above description, attain a stable voltage amplification of several hundred per stage in commercial operation without the necessity of employing any filtering organization to compensate for sharp side-band cut-offs.

It is necessary to commercially realize the above noted results to provide a copious emission of secondary electrons in order that 75 a maximum secondary emission may be obtained to provide the necessary steep characteristic to effectively achieve the well-known negative resistance or dynatron effect.

80 In my co-pending application Serial No. 549,821, filed July 10, 1931, I have illustrated and described the method and means whereby the grid wires and supports may be very highly heated during the tube exhaustion process and I have found that by utilizing 85 this method I am able to vaporize from the grid standards metals of large atomic volume and low atomic number, such as aluminum, boron, and beryllium, or alloys of 90 one or more of these elements and to distill such vaporized metals upon the inner surface of the anode to produce a clean mirror-like metallic surface which is capable of 95 very high secondary electron emission.

By such distillation during the process of 95 out-gassing an uncontaminated surface is obtained in a very short period of time and at a much lower cost than is the case where the entire anode is composed of a metal having high secondary emission properties. In carrying out my invention, I construct the grid supports carrying the beads or small portions of the metal desired to be vaporized, of nickel or molybdenum, both metals having a higher melting point than the metal which is vaporized therefrom. As pointed out in my co-pending application last referred to, I am able to obtain the necessary high temperature by providing on the extremities of the standards or supports of screen grid 10 a wire loop 19 the plane of which is substantially at right angles to the plane of the grid supports which by induction from the radio frequency induction coil used in the process of evacuating the tube picks up sufficient radio frequency energy 100 to heat the grid supports and the grid wires to a higher temperature than that of the anode 8 and the vaporized metal therefor 105 condenses on the anode to form the desired 110 surface.

While I preferably employ for vaporization upon the anode metals such as aluminum, boron, beryllium, or other metals having 115 large atomic volume and low atomic number, I have found that such metals as magnesium may be effectively employed for the same purpose, or in fact any metal having a lower vaporization point than nickel or molybdenum.

The high ratio of secondary tube electron emission depends not only on the nature of the metal as stated in my co-pending application Serial No. 542,494, filed June 6, 1931, 5 but also on the nature of the surface. Consequently, a high ratio of secondary to primary electron emission may be attained either from a metal of low atomic number and large atomic volume, or from a mirror-like uncontaminated surface. Obviously, if 10 the mirror-like uncontaminated surface is formed of a metal of low atomic number and large atomic volume, a maximum high ratio of secondary to primary electron emission 15 is obtained, although quite an efficient ratio of secondary to primary emission may be obtained from a mirror-like uncontaminated surface of metals other than those having low atomic number and large atomic volume 20 vaporized and deposited by distillation as in my present invention upon an anode composed of a metal having a higher melting point than the metal so deposited.

It will be noted from the above that by 25 providing in this manner an anode having a high ratio of secondary to primary electron emission and by providing in close proximity to the inner and outer surfaces of the anode, screening electrodes, that I am able 30 to achieve low values of negative resistance and a high value of controllability with extremely high amplification and that I have in this manner produced a commercially effective thermionic tube utilizing dynatron 35 or negative resistance effect and suitable for use commercially as a high gain radio frequency amplifier.

While I have chosen to describe only one 40 specific embodiment of my invention, it is to be taken merely as illustrative, as obviously various details and the form may be changed without altering the spirit or narrowing the scope of my invention.

Having thus completely described my invention, what I claim as new and desire to 45 secure by Letters Patent of the United States is:

1. An electron discharge device comprising 50 an envelope housing a cathode, a control grid, an anode, a screening electrode closely adjacent to said anode, means for distilling from said screening electrode and depositing by distillation on the surface of said anode, a metal of low atomic number and large 55 atomic volume, and an additional screening electrode located between said first mentioned screening electrode and said control grid.

2. An electron discharge device comprising 60 an envelope housing a cathode, a control grid closely adjacent said cathode, an anode composed of a metal of relatively high melting point and bearing on the surface thereof a coating of a metal having a 65 high secondary to primary electron emis-

sion ratio, screening electrodes closely adjacent to both faces of said anode, and an additional screening electrode located between one of said electrodes closely adjacent to said anode and said control grid. 70
